US0D1056596S

(12) **United States Design Patent** (10) Patent No.: **US D1,056,596 S**
(45) Date of Patent: ** Jan. 7, 2025

(54) **CHAIR BACKREST**

(71) Applicant: **Martin Ballendat**, Simbach (DE)

(72) Inventor: **Martin Ballendat**, Simbach (DE)

(**) Term: **15 Years**

(21) Appl. No.: **29/867,376**

(22) Filed: **Oct. 21, 2022**

(51) LOC (15) Cl. **06-06**

(52) U.S. Cl.

USPC **D6/716.4**

(58) **Field of Classification Search**

(57) **CLAIM**

The ornamental design for a chair backrest as shown and described.

DESCRIPTION

FIG. 1 is a front perspective view of a chair backrest, showing my new design.

FIG. 2 is a rear view thereof.

FIG. 3 is a front view thereof.

FIG. 4 is a right-side view thereof.

FIG. 5 is a left-side view thereof.

FIG. 6 is a top view thereof; and,

FIG. 7 is a bottom view thereof.

The broken lines in FIGS. 1 through 7 show portions of the article that form no part of the claimed design.

1 Claim, 7 Drawing Sheets
